US0D1080191S

(12) United States Design Patent (10) Patent No.: US D1,080,191 S
(45) Date of Patent: * Jun. 24, 2025

(54) WALLET

(71) Applicant: Trias Holding AG, Zug (CH)

(72) Inventors: Beetna Lee, Seoul (KR); Sooha Choi, Seoul (KR)

(73) Assignee: Trias Holding AG, Zug (CH)

() Term: 15 Years

(21) Appl. No.: 35/516,047

(22) Filed: Dec. 20, 2022

(80) Hague Agreement Data

Int. Filing Date: Dec. 20, 2022

Int. Reg. No.: DM/226010

Int. Reg. Date: Dec. 20, 2022

Int. Reg. Pub. Date: Jan. 20, 2023

(51) LOC (15) Cl. 03-01

(52) U.S. Cl.

USPC D3/216; D3/217

(57) CLAIM

The ornamental design for a wallet as shown and described.

DESCRIPTION

1.1: is a front view of a wallet embodying the new design;

1.2: is a rear view of the wallet;

1.3: is a top view of the wallet;

1.4: is a bottom view of the wallet;

1.5: is a left side view of the wallet;

1.6: is a right side view of the wallet;

1.7: is a front perspective view of the wallet;

1.8: is a bottom perspective view of the wallet in an open configuration.

The dash-dash broken lines in the reproductions show stitching. The dash-dot-dash broken lines in the drawing show environmental structure or boundaries that form no part of the design to be patented.

1 Claim, 8 Drawing Sheets
